UNITED STATES PATENT OFFICE.

CHARLES M. STEVENSON, OF ROCKFORD, ILLINOIS, ASSIGNOR TO DREW CARRIER COMPANY, OF WATERLOO, WISCONSIN, A CORPORATION OF WISCONSIN.

STANCHION.

1,132,045.

Specification of Letters Patent. Patented Mar. 16, 1915.

Application filed October 10, 1912. Serial No. 794,371.

To all whom it may concern:

Be it known that I, CHARLES M. STEVENSON, a citizen of the United States, residing at Rockford, in the county of Winnebago and State of Illinois, have invented certain new and useful Improvements in Stanchions, of which the following is a specification, reference being had to the accompanying drawing, forming a part thereof.

10 This invention relates to stanchions and the objects of the invention are to provide an adjustable stanchion and further to provide a simple, efficient and reliable stanchion.

15 Referring to the drawings which accompany this specification and form a part hereof, on which drawings the same reference characters are used to designate the same elements wherever they may appear in each of the several views, and which drawings illustrate an embodiment of this invention, Figure 1 is an elevation of a stanchion, parts being shown in section; Fig. 2 is an elevation of the stanchion seen from one side; Fig. 3 is a section taken on the line 25 *a—a* on Fig. 1, looking in the direction indicated by the arrows; and Fig. 4 is a section taken on the line *b—b* on Fig. 1, looking in the direction indicated by the arrows.

20 The embodiment of the invention illustrated by the drawings and hereinafter specifically described is what I consider the best and preferred form of its embodiment but it will be apparent that mechanical changes can be made without departing from my invention.

25 Referring specifically to the drawings, the reference numeral 1 designates one upright and 2 the other upright. Preferably these uprights are composed of tubes and the upright 1 is U-shaped with the upper end longer than the lower end to allow for the opening of the stanchion in the manner to be hereinafter described. Bifurcated, curved castings 3 and 4 are secured in the ends of upright 2 and adjustable collars 5 and 6 are clamped on the upper and lower horizontal parts of upright 1 by set screws 7 and 8, or other suitable fastening means. The under side of the upper horizontal part of upright 50 1 is provided with a slot 9 into which projects the latch 10 which is pivoted in the bifurcation of casting 3 on pivot 11. The latch has a recess 12 to receive the lower part of collar 5 to lock the upright 2 against

movement either toward or away from upright 1. The latch is retained in engagement with the collar 5 by the spring 13 but can be disengaged therefrom by pressing the handle part 14 of the latch toward the upright 2. The latch is provided with a U-hook 15 to engage with an adjacent member (not shown) to prevent swinging or twisting of the stanchion when it is opened. A stop 16 provided with a slot 17 in its lower side is fastened in the end of the horizontal, upper, tubular part of upright 1 by a set screw 18 or other suitable fastening means and a stop-pin 19 passed through the latch prevents the latch from being entirely withdrawn from the tube when the stanchion is opened.

30 The collar 5 is provided with apertured lugs 20 and 21 for suspending the stanchion and the collar 6 is provided with apertured lugs 22 and 23 for fastening the lower end of the stanchion in any ordinary or preferred manner. The collar 6 has extensions 24 and 25 carrying a collar part 26 which is provided with a lug 27 extending between the parts of the bifurcated casting 4 and 35 this casting is pivoted to this lug by the pivot 28. To adjust the stanchion to make it larger or smaller to accommodate different sized necks of animals, set screws 7 and 8 are loosened and collars 5 and 6 are both 40 moved the required distance in the proper direction and the set screws are then tightened. The collar 5 is provided with a rib 29 which projects into the slot 9 and prevents the slot being closed upon the latch 45 10 and binding the same when the set screw 7 is tightened.

35 What is claimed is:

40 1. An adjustable stanchion composed of an upright provided with upper and lower horizontal portions, the upper one being provided with a slot, adjustable collars on said upper and lower horizontal portions, a second upright pivoted to the lower collar, and a latch extending into said slot in the upper horizontal portion of the first mentioned upright and adapted to engage with the upper collar.

45 2. An adjustable stanchion composed of an upright provided with upper and lower horizontal portions the upper of which is tubular and provided with a slot in its under side, adjustable collars on said upper

and lower horizontal portions, an upright pivoted to the lower collar, and a latch pivoted to the last mentioned upright extending into said slot and adapted to engage the upper collar.

3. An adjustable stanchion composed of an upright provided with upper and lower horizontal portions the upper of which is tubular and provided with a slot in its under side, adjustable collars on said upper and lower horizontal portions, an upright pivoted to the lower collar, a latch pivoted to the last mentioned upright extending into said slot and adapted to engage the upper collar, a stop provided with a slot in the end of the upper horizontal portion of the

first mentioned upright, and a stop-pin carried by said latch.

4. In an adjustable stanchion, the combination with a tubular upright, provided with a slot, of a second upright provided with a latch entering said slot, an adjustable collar provided with a rib projecting into said slot and means for securing said collar upon said first mentioned upright. 20 25

In witness whereof I hereto affix my signature in presence of two witnesses.

CHARLES M. STEVENSON.
